UNITED STATES PATENT OFFICE

2,147,497

ELECTRIC CIRCUIT INTERRUPTER

David C. Prince, Swarthmore, and Percy Bartlett,
Springfield, Pa., assignors to General Electric
Company, a corporation of New York

Application November 11, 1937, Serial No. 174,066

8 Claims. (Cl. 200—150)

Our invention relates to electric circuit interrupters for high voltage power circuits, more particularly to circuit breakers of the impulse type wherein a piston or the equivalent thereof is utilized to project arc-extinguishing liquid through the arc to be interrupted.

Power breakers of the above type have been proposed wherein the arc pressure tending to oppose or block normal operation of the piston is compensated to a certain degree by admitting arc pressure to the opposite side of the piston. While improving the breaker operation, certain difficulties including uncertain interruption at low current values when the arc pressure is very low and improper utilization of the arc pressure are still present.

A principal object of our invention is the provision of an improved circuit breaker of the impulse type that is simple and compact in design, and efficient, rapid and positive in its interrupting operation throughout the entire range of current rating.

Our invention will be more fully set forth in the following description referring to the accompanying drawing, and the features of novelty which characterize our invention will be pointed out with particularity in the claims annexed to and forming a part of this specification.

Referring to the drawing the single figure thereof is an elevational view, partly in section, of an electric circuit breaker embodying our invention.

The circuit interrupter illustrated by way of example comprises a main housing or casing 1 adapted to contain a suitable arc-extinguishing liquid such as oil. Immersed in the arc-extinguishing liquid is an arc interrupting device generally indicated at 2 supported at the lower wall of the housing by an insulator 3. The arc-extinguishing device includes a conducting or fixed contact structure 4 supported in part by a second insulator 5 serving as the lead-in terminal conductor bushing between the fixed contact structure 4 and the exterior circuit. The other terminal of the breaker includes a contact 6 suitably mounted with respect to an insulator 7 that also serves as a lead-in terminal conductor bushing in the wall of the housing 1.

The movable contact structure associated with the arc-interrupting device 2 comprises a contact rod 8 adapted to make sliding contact with the contact 6 and suitably guided for reciprocal rectilinear movement. The means for effecting movement of the rod contact 8 comprises a linkage 55 mounted within a spherical extension 9 of

the main housing, the extension being attached to the housing through an intermediate cylindrical member 10.

The interrupting device 2 including the fixed contact structure 4 is provided with a cylindrical portion 11 open at its opposite ends. A piston 12 is mounted for reciprocal movement within the cylinder and is attached through an insulating rod 13 to the linkage above referred to in the spherical extension 9. The upper end of the arc-interrupting device 2 is closed by a pair of spaced insulating plates 14 and 15 through which the contact rod 8 is moved in aligned apertures 16 to engage the relatively fixed contact structure. The spacing between the plates 14 and 15 forms 15 a lateral passage 17 that communicates at one end through an opening 18 in the plate 15 with one side of the piston 12 and at the other end exhausts into the main housing 1.

Referring more particularly to the contact structure in the device 2 for coating with the rod 8, there is provided an intermediate floating contact 19 disposed between the fixed contact structure 4 and the rod contact 8 arranged so that two arcs are formed in series when the complete contact structure is separated. The intermediate contact 19 is mounted in and supported by an insulating partition 20 forming with the conducting structure 4 pressure chambers 21 and 21' in communication with the lower and upper faces respectively of the piston 12. A vent 20' of suitable bore and location in the partition 20 permits the piston 12 to descend during the closing or resetting stroke. During this movement the chamber 21 is scavenged of residual gases resulting from the preceding arc interruption.

The contact separation within the chamber 21 takes place between the arcing tips 4' of the fixed contact and 19' of the intermediate contact. A spring 22 seated at the opposite side of the partition 20 tends to bias the intermediate contact away from engagement with the contact tip 4'. The intermediate contact is also provided with arcing tip 19" for coating with the 45 rod contact 8 which is illustrated in alignment therewith through the apertures 16. Accordingly, it will be noted that when the rod contact 8 is lowered to close the circuit between the terminals 5 and 7, the intermediate contact will 50 first be engaged and then depressed against the bias of spring 22 until the arcing tips 4' and 19' are in engagement. The circuit is then completed between the terminals. The circuit-opening operation is the converse of that above de- 55

scribed, the contact tips 4' and 19' first separating due to the following movement of the intermediate contact 19 under the influence of spring 22. When the intermediate contact reaches its upper limit of travel, as illustrated, separation of the rod contact 8 and contact tip 19" takes place resulting in a second break in the circuit. This second break is in the transverse passage 17 through which oil is driven by the piston 12 in a manner presently to be described for interrupting the arc.

The operating linkage previously referred to in the housing extension 9 is arranged to cause simultaneously both opening movement of the rod contact 8 and an upward working stroke of the piston 12. By way of explanation the drawing illustrates the mechanism in the process of being closed, piston 12 being first depressed and the rod contact 8 then lowered to engage the contact structure within the arc-interrupting device.

When the breaker is opened, pressure generated by the arc formed between the contact tips 4' and 19' in the pressure chamber 21 acts on the lower side of the piston 12 tending to assist the upwardly pulled piston in driving a stream of oil through the passage 17 transversely of the arc subsequently formed at the contact 8. In the case of arc currents of appreciable magnitude, this operation is very effective and the piston propelled by both mechanical and arc-generated pressures drives a blast of oil at high velocity transversely of the arc within the passage 17.

During the interruption of low currents, however, the generated arc pressure may be of quite a low value or slow in forming. Hence a retardation of the piston would ensue because of its tendency to produce a vacuum or "negative pressure" on its under side during its upward travel. This would lessen the intensity of an early and decisive oil blast through the passage 17. For the purpose of eliminating this hazard a non-return valve 23 is provided for the chamber 21 arranged so that oil is drawn into the chamber from the main housing 1 when the piston 12 tends to create a vacuum in the chamber due to insufficient arc pressure. The valve 23 obviously remains closed when the arc pressure is sufficient to aid the piston 12. That is, the pressure chamber 21 is provided with valve means arranged to close the chamber when the arc pressure therein has or exceeds a predetermined value, and also arranged to open the chamber when said pressure is less than said predetermined value.

Accordingly, the piston is effective throughout the entire range of current rating to project an effective oil blast through the main arc within the passage 17. In the case of heavy current arcs, it will be noted that the piston 12, in moving to the dotted line position shown, establishes a wide communication between chambers 21-21' to form a common pressure region. Because the intermediate floating contact has sealed the lower baffle aperture 16, any pressure persisting in this region is utilized to cause the oil blast to "follow through" although the piston may have completed its own effective stroke.

Thus, it may be particularly noted that the upwardly moving piston 12, biased by spring 35 hereinafter referred to, and the arc generated pressure also acting upwardly on the piston under surface and later independently thereof, are free to merge their respective forces or to act inde-

pendently to the best advantage as current conditions may dictate.

The operating linkage for the contact rod 8 and the piston 12 above referred to may comprise any suitable arrangement for effecting quick separation of the contacts and a positive stroke of the piston. In the present instance, there is shown a main operating shaft 24 transversely journaled in the side walls of the extension casing 9. The shaft 24 is connected to a suitable actuating means exteriorly of the casing and has secured thereto a crank arm 25. The arm 25 is pivotally connected to an adjustable link 26 that is in turn connected to a lever 27. The lever 27 at one end is pivotally connected to a link 28 intermediate the ends thereof that is in turn pivotally mounted at one end with respect to a fixed fulcrum at 29. At its opposite end it is pivotally connected to a link 30 near the mid-portion thereof, the link 30 also being pivotally connected at 31 to the upper end of the contact rod 8.

The lever 27 is also pivotally connected to a floating lever 32 that is in turn loosely connected to the insulating rod 13 of the piston 12. A pin 33 at one end of the link 30 operates in a slot 32' in the floating lever 32, the movement of the opposite end of the floating lever being controlled in one direction by an abutment 34.

The linkage is shown in a partially closed position in which the operating shaft 24 has been rotated counter-clockwise towards the circuit closing position so as to extend or charge the spring 35. The spring in this position biases the piston 12 through the insulating rod 13 in an upward or blast-producing direction. Further clockwise rotation of the shaft 24 will cause the lever 27 to rotate the link 28 also in a counter-clockwise direction thereby rotating the link 30 clockwise and moving the contact rod 8 downward into contact engagement within the arc-interrupting device. This operation also will extend the biasing spring 36 tending to move the contact rod 8 in a circuit-opening direction.

The circuit breaker as described is now in the closed circuit position wherein the contact rod 8 is biased by the spring 36 in the circuit opening direction, and the piston 12 is similarly biased by the spring 35 in a direction to cause an oil blast across the arc when the contacts separate.

The shaft 24 in the circuit-closing operation is rotated to a point so that the crank arm 25 and link 26 are slightly overset so as to hold the breaker in the circuit-closing position. In the circuit-opening operation the shaft 24 is rotated in a clockwise direction so that the linkage will be released and the springs 35 and 36 are effective to cause simultaneous movement of the contact rod 8 and piston 12 upward, thereby causing separation of the breaker contacts and extinguishing of the arc.

It should be understood that our invention is not limited to specific details of construction and arrangement thereof herein illustrated, and that changes and modifications may occur to one skilled in the art without departing from the spirit of our invention.

What we claim as new and desire to secure by Letters Patent of the United States, is:

- An electric circuit breaker of the impulse type comprising an arc-extinguishing liquid, relatively movable contact structure adapted to form two breaks in series in said liquid upon opening of the circuit, means defining a pressure chamber within which one of said breaks is formed,

5 a piston communicating with said chamber and arranged to project arc-extinguishing liquid through the arc at said other break, means for actuating said piston independently of said arc pressure, and means for compensating low arc pressure in said chamber when said piston tends to create a negative pressure therein.

10 2. An electric circuit breaker of the impulse type comprising an arc-extinguishing liquid, relatively movable contact structure adapted to form two breaks in series in said liquid upon opening of the circuit, means defining a pressure chamber within which one of said breaks is formed and a transverse passage within which the other of said breaks is formed, a piston interposed between said chamber and said passage arranged so that arc pressure in said chamber tends to move said piston in a direction to cause a blast of arc-extinguishing liquid through said passage for interrupting the arc at said other break, means for actuating said piston independently of said arc pressure, and a valve associated with said chamber for compensating low arc pressure therein when said piston tends to create a negative pressure in said chamber.

15 3. An electric circuit breaker of the impulse type comprising an arc-extinguishing liquid, relatively movable contact structure including a fixed contact, an intermediate contact and a main movable contact adapted to form two breaks in series 20 in said liquid upon opening of the circuit, means defining a pressure chamber within which the break between said fixed and intermediate contacts is formed, said intermediate contact coating with said main movable contact exteriorly of said chamber, a piston communicating with said chamber and arranged to project arc-extinguishing liquid through the arc at the break between said intermediate and main movable contacts, the arc pressure in said chamber tending to aid said projection of arc-extinguishing liquid through said other arc, means for actuating said piston independently of said arc pressure, and valve means controlling a port in said chamber arranged to close said chamber in the case of heavy 25 current interruptions whereby said piston is assisted by the resulting arc pressure.

40 4. An electric circuit breaker of the impulse type comprising an arc-extinguishing liquid, an arc-interrupting device immersed in said liquid having a pressure chamber and a transverse exhaust passage, a fixed contact disposed in said chamber, a floating contact coating therewith and extending through a wall of said chamber, a movable contact coating with said floating contact exteriorly of said chamber in said exhaust passage, a piston interposed between said chamber and passage arranged so that arc pressure formed in said chamber between said fixed and floating contacts tends to drive arc-extinguishing liquid through said passage and transversely of the arc between said floating and movable contacts, means for actuating said piston independently of said arc pressure, and means associated with said chamber for compensating low arc pressure in said chamber when said piston tends to create negative pressure therein.

45 5. An electric circuit breaker of the impulse type comprising an arc-extinguishing liquid, relatively movable contact structure including a fixed

5 contact, an intermediate contact and a main movable contact adapted to form two breaks in series in said liquid upon opening of the circuit, means defining a pressure chamber within which the break between said fixed and intermediate contacts is formed, a non-return valve associated with said pressure chamber, said intermediate contact coating with said main movable contact exteriorly of said chamber, a piston communicating with said chamber and arranged to project arc-extinguishing liquid through the arc at the break between said intermediate and main movable contacts, the arc pressure in said chamber tending to aid said projection of arc-extinguishing liquid through said other arc, and means for actuating said piston independently of said arc pressure.

10 6. An electric circuit breaker of the impulse type comprising an arc-extinguishing liquid, relatively movable contact structure adapted to form two breaks in series upon opening of the circuit, means defining a pressure chamber within which one of said breaks is formed in said liquid, a piston communicating with said chamber and arranged to project arc-extinguishing liquid through the arc at said other break, means for actuating said piston independently of the arc pressure in said chamber, and means for opening said chamber to a low pressure region in said liquid when said arc pressure is less than a predetermined value.

15 7. An electric circuit breaker of the impulse type comprising an arc-extinguishing liquid, relatively movable contact structure immersed in said liquid and adapted to form two breaks in series upon opening of the circuit, means defining a pressure chamber within which one of said breaks is formed, means forming an interrupting chamber within which the other of said breaks is formed, a piston communicating with both chambers and arranged to project arc-extinguishing liquid through the arc in said interrupting chamber, the arc pressure in said pressure chamber tending to aid said projection of arc-extinguishing liquid, means for actuating said piston independently of said arc pressure, and valve means coating with said pressure chamber arranged to be closed when said arc pressure has or exceeds a predetermined value, and arranged to be opened when said arc pressure is less than said predetermined value.

20 8. An electric circuit breaker of the impulse type comprising an arc-extinguishing liquid, relatively movable contact structure adapted to form two breaks in series upon opening of the circuit, means defining a pressure chamber within which one of said breaks is formed in said liquid, a piston communicating with said chamber and arranged to project arc-extinguishing liquid through the arc at said other break, actuating means for effecting a working stroke of said piston, and valve means controlling a port in said chamber communicating with a region exteriorly thereof, said valve means being arranged to open said port to prevent retardation of said piston due to insufficient arc pressure in said chamber and to assist the working stroke of said piston at high arc pressure by closing said port.
